SPECTACLE CASE

Benjamin Grosvenor, Pomfret, Conn., assignor to
 American Optical Company, Southbridge,
 Mass., a voluntary association of Massachusetts

Application December 16, 1948, Serial No. 65,660

1 Claim. (Cl. 206—5)

1

The invention relates to spectacle cases and has particular reference to cases of the type formed of sheet material folded so as to provide a receptacle for spectacles, and method of making the same.

An important object of the invention is to provide an improved spectacle case formed of leather, fabric, plastic or other suitable flexible sheet material which can be initially shaped as a blank stamped or otherwise cut out of the desired sheet material, and folded so as to form a pouch having front and rear walls, which walls can be detachably secured so as to maintain their folded positions with respect to one another and method of making the same.

Another object is to provide a spectacle case of the above character which embodies a body of sheet material cut to the desired size and shape and folded so as to present overlapping front and back portions, said back portions being of greater length than said front portion and being folded to form a flap overlying said front portion, and connecting means enclosing the ends of said front and back portions detachably secured to said portions for reinforcing the same.

Another object is to provide a spectacle case of the above character embodying front and back portions disposed in superimposed relationship, said portions having vertical slots formed therein with detachable connecting means threaded through said slots to detachably join and reinforce said portions.

Another object is to provide a spectacle case of the above character embodying a one-piece body element of a preferred material and of a preferred color, which element is folded to form the desired receptacle and secured in folded position by elongated connecting members which may be of a contrasting material and/or color for decorative as well as reinforcing purposes.

Another object is to provide a spectacle case of the above character which can be formed of sheet material so shaped as to require the use of a minimum amount of material and adapted to be manufactured at relatively low cost.

Other objects and advantages will become apparent from the following description taken in connection with the accompanying drawings, in which:

Fig. 1 is a front elevational view of a preferred embodiment of the invention;

2

Fig. 2 is an end view of the embodiment illustrated in Fig. 1;

Fig. 3 is a rear elevational view of the embodiment illustrated in Fig. 1;

5 Fig. 4 is a plan view of the blank from which the body portion of the preferred embodiment is formed;

Figs. 5 and 6 are fragmentary plan views of two forms of connecting members used for securing the folded parts of the spectacle case in position;

Figs. 7 and 8 are front elevational views of modified forms of spectacle cases in accordance with the present invention; and

10 15 Fig. 9 is a fragmentary sectional view of a portion of the inner surface of one of the panels and illustrating particularly the method of securing the ends of the connecting members in place.

Referring to the drawings, wherein like char-

20 acters of reference designate like parts throughout the several views, the preferred embodiment of the invention as shown in Fig. 1 comprises a one-piece body element shaped substantially to the shape illustrated in Fig. 4 and formed of a

25 blank which may be stamped or otherwise cut out of flexible sheet material of the type desired such as leather, fabric, plastic or the like and consists of a back panel portion 10, a front panel portion 11 of substantially the same width as

30 35 the back panel portion, and a tapering closure flap portion 12. The front panel portion 11 and back panel portion 10 are folded so that the fold will be located at the bottom to form a pouch or pocket and the closure flap portion 12 folded downwardly in overlapping relation to the front surface of the front panel 11, as illustrated in Fig. 1, to form a cover for the top opening of the pouch.

To seal the ends of the pouch there is provided

40 45 an elongated connecting member or strap 13 (Fig. 5) which is adapted to extend longitudinally across the outer surface of the front panel 11, the front panel 11 being provided with spaced pairs of vertically disposed slits 14 through which

50 55 the strap 13 is threaded with the major portion of the tab 13 midway of the panel and the portions adjacent each end thereof being disposed on the outer surface of the panel. The strap 13 is of sufficient length to extend around the ends

55 60 of the pouch, its portions adjacent its ends disposed in overlying relation to the back panel 10,

The straps 13 are provided with enlarged end portions 15 which are adapted to project inwardly of the pouch through slits 16 formed in the back panel 10, the slits 16 being substantially shorter than the width of the end portions 15 of the straps 13 so that the tabs 13 will be held securely therein. The end portions 15 of the straps 13 may be shaped in various manners such as by providing them with a substantial "arrowhead" design such as illustrated in Fig. 6, the important factor being to provide the enlarged portion 15 with a width greater than the length of the slits 16. Such a means for detachably securing the straps 13 to the adjacent panel of the pouch is shown in Fig. 9 wherein it can be seen that only the enlarged end portion 15 resides within the interior of the pouch.

A snap fastener 17 such as a type embodying co-operative male and female elements serves to retain the flap 12 in fixed relation to the front panel 11. The male element 18 is preferably secured by conventional means to both the front panel 11 and the strap 13 thereby providing additional means for retaining the strap 13 in desired position with respect to the front panel 10, with the female element 19 mounted in the closure flap 12 being adapted to cooperate with the element 18 to position the flap 12 so as to prevent spectacles carried by the resultant case from becoming dislocated.

A block 20 of suitable size and shape (Fig. 2) may be cemented or otherwise secured within the pouch to the front or back panel or both to partition the pouch for providing means for locating a pair of spectacles in the pouch. The spectacles are placed in the pouch with the nose pads thereof embracing the block 20 and the temples are folded into closed position with respect to the lenses so that the spectacles will rest properly in the pouch. The block 20 serves as well to protect the spectacles from damage due to pressure which may be applied in closing the snap fastener 17.

It is sometimes desirable to entirely eliminate the snap fastener 17 and in such a case the closure flap 12 may be formed substantially to the shape shown in dot-dash outline in Fig. 4. In this modified construction the flap 12 may be inserted between the locking tab 13 and the central portion of the front panel 11 as shown in Fig. 8.

The spectacle case illustrated in Fig. 7 is formed similarly to the preferred embodiment. However, the strap 13 in the modified form is adapted to extend entirely across the outer surface of the back panel 10, around the ends of the pouch and has portions extending part way across the outer surface of the front panel 11, with the end portions 15 being inserted through the slits 16, which in this instance are formed in the front panel, and anchored therein. In such a case the back panel 10 is preferably provided with means such as the spaced paired slits 14 through which the strap 13 will be threaded and so prevented from displacement.

In producing a spectacle case in accordance with the construction illustrated in Fig. 1, the body portion forming the pouch will be preferably initially stamped from the desired flexible sheet material and the slits 14 and 16 will preferably be formed simultaneously to the blanking out operation. If the spectacle case is to be constructed in accordance with the design illustrated in Fig. 7 the preferred initial procedure to be followed will be similar to that for the preferred case with the

exception that the slits will be positioned substantially as shown in dotted outline in Fig. 4 rather than as shown in solid outline as for the preferred embodiment as per Fig. 1.

It will be understood that the straps 13 will substantially reinforce the front and back panels 10 and 11 respectively. The straps 13 may be formed of a material and color similar to the body portion of the spectacle case but for providing additional reinforcing means for the panels they may be formed of a different material, if desired, such, for example, as forming them of a light flexible metallic or plastic material for reinforcing a pouch formed of fabric or the like. In addition to this desirable feature, the straps 13 may be provided in contrasting colors to the body portion of the pouch which will increase the decorative effect to enhance the appearance of the final product.

The foregoing specification describes an improved spectacle case formed of sheet material having its front and back portions retained in position with respect to one another by simple and efficient detachable connecting means which connecting means provides reinforcing means for the case as well as decorative effect therefor.

While certain novel features of the invention have been shown and described and are pointed out in the annexed claim, it will be understood that various omissions, substitutions and changes in the formation and details of the device illustrated and in its use may be made by those skilled in the art without departing from the spirit of the invention.

I claim:

A stitchless spectacle case comprising a body portion formed of a one-piece blank of flexible sheet material folded along a first line of fold to form a pouch having a front panel and a rear panel and with open sides and top, the rear panel having an extended portion foldable over the outer surface of the front panel as a flap to cover the open top of said pouch, connection means carried by said front panel and said flap for detachably connecting said flap in place on the outer surface of said front panel, and spacer means secured interiorly of the pouch to one of said panels adjacent the first line of fold and substantially centrally of the opposed sides thereof, said front and rear panels each having spaced slits disposed approximately normal to said first line of fold, said slits on each panel being located on opposite sides of said centrally secured spacer means and inwardly of the open sides of the pouch, and a strap-like member having portions of a width no greater than and being capable of being threaded in said slits and terminating in enlarged opposed ends having a width greater than the length of said slits to provide abutment surfaces on the side of said enlarged ends opposite the end surface thereof and which extend outwardly of the opposite sides of the adjacent portions of the strap-like member, and said strap-like member being threaded through the spaced slits in one of said panels in such manner that each of its opposed end portions extend over the outer surface of said panel between the respective side thereof and the slit nearest said side, thence being wrapped about the open sides of the pouch onto the outer surface of the other panel and having its ends extended through the respective slits of said other panel nearest to the respective side of the pouch about which said end portions are wrapped, said enlarged ends lying on the inner surface of said panel in spaced

relation with each other on opposite sides of said spacer means and concealed from view, said abutment surfaces of said enlarged ends overlying the inner surface of said panel beyond the opposed ends of the respective slits, whereby the strap-like member will function to close the sides of the pouch and maintain the panels in their folded relation while at the same time being readily interchangeable without destruction of parts.

BENJAMIN GROSVENOR.
